(57) **CLAIM**

The ornamental design for a “lavatory pedestal for a sink”, as shown and described.

DESCRIPTION

FIG. 1 is a front perspective view of a preferred embodiment of a lavatory pedestal for a sink showing our new design; FIG. 2 is a bottom view of the lavatory pedestal for a sink of FIG. 1, shown on a greatly enlarged scale.

FIG. 3 is a front view of the lavatory pedestal for a sink of FIG. 1;

FIG. 4 is a right side view of the lavatory pedestal for a sink of FIG. 1;

FIG. 5 is a top view of the lavatory pedestal for a sink of FIG. 1, shown on a greatly enlarged scale.

FIG. 6 is a left side view of the lavatory pedestal for a sink of FIG. 1; and,

FIG. 7 is a rear view of the lavatory pedestal for a sink of FIG. 1.
